Primary Examiner—Melody N. Brown*(74) Attorney, Agent, or Firm*—Christensen O'Connor Johnson Kindness PLLC(57) **CLAIM**

The ornamental design for a truck hood, as shown and described.

DESCRIPTION

FIG. 1 is a front perspective view of a truck hood showing our new design;

FIG. 2 is a top plan view of the truck hood of FIG. 1;

FIG. 3 is a bottom plan view of the truck hood of FIG. 1;

FIG. 4 is a front elevational view of the truck hood of FIG. 1;

FIG. 5 is a rear elevational view of the truck hood of FIG. 1;

FIG. 6 is a left side elevational view of the truck hood of FIG. 1; and,

FIG. 7 is a right side elevational view of the truck hood of FIG. 1.

The broken lines in the drawings form no part of the claimed design.
